LEVELING BRIDGE

Werner H. Bothe, Kenosha, and Herman J. Miller,
Cudahy, Wis., assignors to Worldsbest Industries, Inc., Cudahy, Wis., a corporation of Wisconsin

Application February 28, 1951, Serial No. 213,074

2 Claims. (Cl. 45—24)

1

This invention relates to stretching frames for use in drying curtains and other fabrics.

The object of the invention is to provide a levelling bridge for stretching frames and more particularly to provide certain improvements over the levelling bridge shown and described in the copending application Serial No. 172,954, filed July 10, 1950, of Werner H. Bothe, for "Levelling Bridge." In said application, the bridge structure is clamped to the adjusting bar or post by a clamp which extends laterally from the front side of this bar, and this has been found objectionable because it limits the available stretching length of the frame since some clearance has to be allowed between said adjusting bar and the unpinned end bar of the frame in order to manipulate the clamp. One of the objects of the present invention is to eliminate the above mentioned objection by providing bridge clamping means which act to clamp the pin carrying bridge plate to the back side of said adjusting bar by exerting a clamping pressure on the front side of the bar.

A further object of the invention is to provide a levelling bridge in which the bridge member itself under the action of the bridge clamp holding it to the adjusting bar also exerts a clamping pressure upon the bottom bar through the leverage action of the pivoted bridge member.

The invention further consists in the several features hereinafter set forth and more particularly defined by claims at the conclusion hereof.

In the drawings:

Fig. 1 is a plan view of a levelling bridge structure embodying the invention showing it applied to a stretching frame;

Fig. 2 is a vertical sectional view taken on the line 2—2 of Fig. 1, parts being broken away;

Fig. 3 is a vertical sectional view taken on the line 3—3 of Fig. 1;

Fig. 4 is a view similar to Fig. 1 showing certain modifications;

Fig. 5 is a sectional view taken on the line 5—5 of Fig. 4.

In stretching frames in which the curtains or other fabric to be dried are impaled on pins mounted in some of the frame members, the so-called vertical adjusting bar or post 6 provided with pins 7 forms a frame corner with the horizontal rail or bar 8 overlying the bar 6 and provided with pins 9, said bar 8 being adjustably clamped to the left hand end bar or post and also to the bar 6 by suitable clamping means. As herein shown, a U-shaped clamping member 10 straddling the bar 6 carries a threaded rod

2

or bolt 11 provided with a clamping nut 12, and an angled clamping member 13 apertured to receive the rod 11 is brought into engagement with both bars 6 and 8 when the nut 12 is clamped down against its top leg 14, a spring 15 being interposed between the members 10 and 13 to facilitate release of these members when the nut 12 is loosened. With the bars 6 and 8 clamped in position as above described the sets of pins 7 and 9 are vertically spaced from each other at the corner joint formed between these bars so that ordinarily the pins 7 adjacent the bar 8 are not effective to hold the fabric being stretched and to provide an effective pinning area at this 15 part of the frame a pin carrying leveling bridge is used.

In each of the forms shown herein, a levelling bridge comprises a pin carrying plate 16 in the form of an angled plate having one side 17 extending parallel to the bar 6 and its other side formed to provide spaced ears or projections 18 in each of which the shank of a pin 19 is anchored, the disposition of the pins 19 being such that when the side 17 of said plate is brought

20 into close or abutting relation with the front edge of the bar 6, the pins 19 will be aligned with the pins 7, and some of these pins 19 will be disposed between some of the pins 7 as shown in the drawings, and both sets of pins 19 and 7 are 25 functioning together for a portion of the length of the levelling bridge. The levelling bridge 16 is secured in each instance to the bar 6 by clamping means in the form of a channel member 20, one of whose legs or sides 20a has the bridge 16 pivots connected thereto, intermediate its ends, by a pin 21 and the other of whose legs or sides 20b has an angled top extension 22. The squared portion at the head end of a carriage bolt 23 is mounted in a square hole 24 in said 30 extension to prevent relative rotary movement and carries a clamping nut 25. A U-shaped clamping plate 26 provided with feet 27 straddles the extension 22 and has a hole 28 through which the threaded shank of the bolt 23 is slidably 35 mounted. The nut 25 bears against the bridge portion of the plate, and on being tightened moves the feet 27 down against the top portion of the bar 6 and pulls up on the head of the bolt 28 and through it draws the base of the channel member 20 against the under side of the bar 6, thus tightly 40 clamping the bridge 16 to the bar 6, and as the wing nut 25 is disposed over the front face of the bar 6, it does not interfere with the lateral adjustment of this bar to a position adjacent the 45 right hand post (not shown) of the stretching

50 55

frame, so that the range of adjustment of this bar is not curtailed as in the aforementioned application. A spring 29 is interposed between the extension 22 and the member 26 to facilitate release of the clamping means. In the form shown in Figs. 4 and 5 the bridge member 16 is similar to that of the application above referred to and is adapted in its operative position to abut the front edge of the bar 8.

The bridge member 16, shown in Figs. 1 and 2, has a tongue or finger 30 which when the bridge is in position engages over the rabbeted front face 31 of the bar 8 and exerts a clamping pressure on this bar as it is clamped to the bar 6, and this is the preferred construction. With this construction as the channel member 20 is pulled up against the bottom of the bar 6, the clamping pressure exerted on the extension 22 tends to cant the leg 20a outwardly from said bar 6, thus moving the pivot 21 and finger carrying end of the bridge downwardly or toward the bottom of the bar 8 to grip the finger 30 with said bar 8 if the parts are correctly positioned relative to each other, but even if they are not so positioned that said finger 30 does not actually grip the bar 8, it will still act as a stop to prevent downward movement of the finger carrying part of the bridge relative to the bar 8 under the action of stretching pressures applied to the pins 19 by the fabrics being stretched.

We desire it to be understood that this invention is not to be limited to any particular form or arrangement of parts except in so far as such limitations are included in the claims.

What we claim as our invention is:

1. In a stretching frame having angularly disposed and joined pin carrying frame members with one of said frame members overlying the other frame member, the combination of a chan-

nel supporting member extending around the bottom and sides of the underlying frame member, a pin carrying levelling bridge carried on one side of the leg of said channel member disposed adjacent the front side of said underlying frame member, the other leg of said channel member having an angled extension overlying the front face of said underlying frame member, a clamping member distinct from said bridge and engageable with the front face of said underlying frame member adjacent said extension, and means connected with said angled extension for drawing said clamping member and the bridge portion of said channel member into clamping engagement with said underlying frame member to clamp said levelling bridge in position at the joint between said members to provide an inclined pinning path between pins of said frame members.

2. The structure as defined in claim 1 in which the levelling bridge is pivotally connected intermediate its ends to the aforementioned leg of said channel supporting member for swinging movement in a plane substantially parallel to the front side of said underlying frame member.
